UNITED STATES PATENT OFFICE

SAUL RITTER, OF NEW YORK, N. Y.

DESIGN FOR A BRACELET CHAIN

Application filed October 24, 1931. Serial No. 41,516. Term of patent 7 years.

To all whom it may concern:

Be it known that I, SAUL RITTER, a citizen of the United States, residing in New York, in the county of New York and State of New York, have invented a new, original, and ornamental Design for a Bracelet Chain, of which the following is a specification, reference being had to the accompanying drawings, forming part thereof.

Fig. 1 is a plan view of a section of con-

nected links embodying the present ornamental design;

Fig. 2 is a side elevational view of the connected links shown in Fig. 1 and

Fig. 3 is an enlarged perspective view of several of the links shown in Fig. 1.

I claim:

The ornamental design for a bracelet chain as shown.

SAUL RITTER.
